TOOL ATTACHMENT

Hugh M. Hodge, Detroit, Mich., assignor of
one-half to George A. Vis, Detroit, Mich.

Application October 17, 1934, Serial No. 748,613

10 Claims. (Cl. 164—118)

The present invention relates in general to improvements in the art of manufacturing machine tools, and relates more specifically to improved means for removably attaching perforating tools 5 such as punches and dies, to their positioning and supporting members.

Generally defined, an object of the present invention is to provide simple and highly effective instrumentalities for removably securing certain 10 tools such as punches or dies, to their carrier members.

It is of extreme importance in the art of perforating sheet materials with the aid of complementary punches and dies that perfect registry 15 of the coacting tools be maintained at all times, and that these tools be readily replaceable. Depending upon the shape of perforations desired, the punches frequently assume odd shapes, and regardless of the shape thereof, they must register with the similarly shaped receiving dies with 20 utmost precision. Because of the fact that it is frequently necessary to change the shape and size of the perforations, it is prerequisite that the perforating tools be readily interchangeable 25 with others, while at the same time maintaining rigid attachment of these tools to their supports when in use. The prior tool attachments of this general type, besides being relatively complicated, did not permit convenient application of the tools 30 to their carrier members and subsequent removal therefrom and, moreover, did not insure the requisite precision of registry necessary to insure perfect perforating and to eliminate breakage of the cooperating tools.

It is therefore a more specific object of the present invention to provide an improved tool attachment which meets all of the above-men-

tioned desirable requirements, and which eliminates all of the objectionable features of prior 40 attachments of this type.

Another specific object of the invention is to provide an improved fastening means for perforating tools or the like, which may be applied with advantage to tools or dies of various types 45 to provide a readily removable, simple, and rigid attachment.

A further specific object of the invention is to provide a new and useful fastening for the punches and dies of perforating machines, which may be 50 readily manufactured and subsequently manipulated, and which utilizes relatively standard attaching elements.

Still another specific object of the invention is to provide an attachment wherein a minimum 55 number of relatively simple attaching elements

are utilized to firmly but removably fasten both a tool and its positioning block to a common supporting member for both the tool and block.

A further specific object of the invention is to provide a durable fastening which is readily applicable to perforating presses and machines of different kinds, and which may be furnished at minimum cost. 5

These and other objects and advantages will be apparent from the following detailed description. 10

A clear conception of several embodiments of the invention, and of the mode of constructing and of applying the improved tool attachment to the punches and dies of perforating machines, 15 may be had by referring to the drawing accompanying and forming a part of this specification, in which like reference characters designate the same or similar parts in the various views.

Fig. 1 is a part sectional side elevation of a plurality of punches showing the same secured with the improved attachments to a common positioning block and to a fragment of the punch supporting member; 20

Fig. 2 is a sectional view of a plurality of dies 25 cooperable with the respective punches of Fig. 1, and showing the dies likewise secured with the aid of the improved attachments to a common positioning block and to a fragment of the die supporting member; 30

Fig. 3 is a sectional view of a single punch attachment embodying the present improvement; 35

Fig. 4 is a bottom view of the assemblage shown in Fig. 3, a section having been taken thru the punch along the line 4—4;

Fig. 5 is a sectional view thru a modified type of attachment for a perforating punch; and

Fig. 6 is a bottom view of the assemblage shown in Fig. 5. 40

While the invention has been shown and described herein as being specifically applied to punches and dies for producing circular perforations, it is not intended to restrict the scope by such specific disclosure since the improvements are obviously more generally applicable to other 45 types of perforating tools and machine elements.

Referring specifically to Fig. 1 of the drawing, the four circular punches 1 are of the same general type but of different effective diameters, and these punches 1 are simultaneously cooperable 50 with dies 8 of the type shown in Fig. 2, to punch a series of holes into a sheet of material. Each of the punches 1 has an enlarged polygonal or cylindrical shank portion 9 adapted to snugly engage a properly located bore or hole 10 in the 55

common positioning block 11, and this block 11 coacts with a combined gage and reaction plate 12 which, in turn, coacts with the main punch supporting member 13.

5 The block 11 and plate 12 may be definitely positioned relative to the supporting member 13 by a pair of end dowels 14, and the positioning block 11 and reaction plate 12 may in some cases be directly attached to the member 13 by 10 one or more ordinary cap screws 15. These cap screws 15 may, however, be dispensed with in favor of one or more punch-attaching cap screws 16, such as shown to the left of Fig. 1, and the screws 16, besides serving as attaching means for 15 the block 11 and plate 12, also serve to lock the punches 7 with which they coact, within the holes 10 and against the plate 12. Other punch-attaching cap screws 17 which coact only with the punches 7 and with the positioning block 11 20 may be employed either in conjunction with or in lieu of the attaching screws 16, in order to insure firm attachment of the punches 7 to their carrying structure.

25 Each of the punch-attaching screws 16, 17 is provided with a polygonal or cylindrical head 18 having a central polygonal socket 19 therein for the reception of a manipulating plug wrench, and the side of each screw head 18 is provided with one or more cut-outs 20. Each of the punch shank portions 9 is provided with one or more lateral recesses or cut-out portions forming abutments 21, and the screw heads 18 are adapted to coact with these abutments 21 when the punches are locked in place. When the screws 16, 17 are 30 rotated to bring the cut-outs 20 directly adjacent to the corresponding punch shanks, the punches 7 are released and may be freely removed from or inserted within the shank receiving holes 10.

35 In Fig. 2 of the drawing the same general method of attachment has been applied to the dies 8. Each of the dies 8 is hollow to accommodate the discharge of stock removed during perforation and has an enlarged polygonal or cylindrical shank portion 22 adapted to snugly fit a 40 properly positioned hole 23 in the common positioning block 24. The block 24 coacts with a combined gage and reaction plate 25 which, in turn, rests upon a main die supporting member 26, and both the plate 25 and member 26 are 45 provided with openings which register with the central openings of the dies 8.

50 The block 24 and plate 25 may be definitely located with respect to the supporting member 26 by a pair of dowels 14, and the positioning block 24 and reaction plate 25 may, if desired, be directly attached to the member 26 by one or more ordinary cap screws 15. These attaching screws 15 may, however, be dispensed with in lieu of one or more die-attaching cap screws 55 16 of the type shown to the left of Fig. 2, and the screws 16, besides serving as means for securing the block 24 and plate 25 in place, also serve to simultaneously lock the dies 8 with which they coact, within the holes 23 and against the plate 25. Other die-attaching cap screws 17 which coact only with the dies 8 and with the 60 positioning block 24 may be used either in conjunction with or in place of the attaching screws 16, in order to further insure rigid attachment of the dies 8 to their supporting structure.

65 Each of the die attaching screws 16, 17 may likewise be provided with a polygonal or cylindrical head 18 having a central polygonal socket 19 therein for receiving a manipulating plug wrench, and the side of each screw head 18 is

70 provided with one or more lateral cut-outs 20. Each of the die shank portions 22 is provided with one or more cut-outs forming abutments 21, and the locking screw heads 18 are adapted to coact with these abutments when the dies 8 are locked in position. When the screws 16, 17 are rotated to cause the cut-outs 20 to be positioned directly adjacent to the corresponding die shanks, the dies 8 are released and may be freely withdrawn from or inserted within the die 10 receiving holes 23.

75 The punch and die supporting members 13, 26 are relatively movable during normal operation of the perforating press, to cause the punches 7 to enter and to be subsequently withdrawn from the corresponding dies 8. The degree of entry may be varied either by changing the extent of movement of the members 13, 26, or by replacing the gage and reaction plates 12, 25 with others having different thickness. The pin dowels 14 20 definitely position the blocks 11, 24 and the plates 12, 25 relative to the supporting members 13, 26, and the blocks 11, 24 definitely position the punches 7 and dies 8 with respect to each other so as to insure perfect registry of the perforating tools. The attaching screws 16, 17, while affording a rigid attachment of the punches 7 and dies 8 to their supporting elements during normal use of the press, however, also permit rapid and convenient removal and reinsertion of the perforating tools with respect to the positioning blocks 11, 24 and plates 12, 25 whenever desired. The cut-outs 20 in the screw heads 18 obviously serve to permit such removal and insertion without necessitating complete withdrawal of the screws 16, 17, thereby permitting the use of the screws 16 alone for the purposes of clamping the tools in place and of attaching the positioning blocks 11, 24 and plates 12, 25 to the carrier members 40 13, 26.

80 With reference to Figs. 3 and 4, a single punch 7 is shown therein having its shank portion 9 cooperating with a bore 10 in the positioning block 28. This block 28 is cylindrical in form and co- 45 acts with a reaction plate 29 which, in turn, coacts with a supporting member 30. Dowels 14 are again employed for the purpose of definitely positioning the block 28 and plate 29 relative to the member 20; and the removable attachment 50 of the punch 7 to the block 28, and of the block 28 and plate 29 to the support, is effected by the clamping screws 16 alone. As in the disclosure of Figs. 1 and 2, the screws 16 of Figs. 3 and 4 are again provided with socketed heads 18 co- 55 operable with abutments 21 formed on the punch shank, and these screw heads 18 likewise have lateral cut-outs 20 for facilitating insertion and removal of the punch 7.

85 In Figs. 5 and 6 is shown a small single punch 60 7 having a modified type of attachment applied thereto. The punch 7 has a cylindrical shank portion 9 snugly fitting a bore 10 in a rectangular positioning block 31, and this block coacts with a reaction plate 32 which, in turn, coacts with the 65 main supporting member 33. The block 31 and reaction plate 32 are properly positioned relative to the supporting member 33, by means of pin dowels 14; and a single attaching screw 34 coacts with the punch 7, block 31, and plate 32 in order to 70 lock these elements to the member 33. The screw 34 has a substantially cylindrical head 35 provided with a transverse manipulating slot 36, and having a side cut-out 37. The screw head 35 is adapted to coact with a shoulder or abutment 21 formed 75

on the shank portion 9 of the die, and when the screw 34 is rotated with the aid of a screw driver applied to the slot 36, so as to position the cut-out 37 in line with the side surface of the shank, 5 the punch 7 may be readily removed from or inserted within the bore 10. This embodiment of the improvement differs from those previously described merely in the formation of the clamping screw 34, and this screw may assume still different forms without departing from the spirit of 10 the invention.

From the foregoing description, it will be apparent that the present invention provides simple means for firmly but detachably securing a perforating tool such as a punch or a die to its supporting or carrying structure. The same element that is utilized to hold the tool in place may also serve to hold the positioning block and reaction plate against the supporting member, and the tool 15 may be removed without disturbing the block and plate. A single attaching screw may also be utilized to fasten several tools to a common support, and the improved assemblage insures utmost precision in coaction of the punches with the dies. 20 The improved clamping screws may be readily manufactured and applied to any punch or die assemblage at moderate cost and may also be conveniently manipulated for rapid withdrawal of the tools with which they cooperate. It is also 25 noteworthy that the coaction of the clamping screw with a cut-out or notch in the side of the perforating tool positively prevents the tool from rotating, thereby making the attachment especially applicable to polygonal punches and dies. 30 Another very important feature of the present invention is that the attaching screws for the perforating tools may be extended directly into the main supporting member closely adjacent to the tools, thereby transmitting the stripping forces directly to the main supporting member and not 35 thru the positioning block and clamping screws located remote from the tools, as in the prior attaching devices.

It should be understood that it is not desired to 40 limit the invention to the exact details of construction, and to the precise mode of operation herein shown and described, for various modifications within the scope of the claims may occur to persons skilled in the art.

50 It is claimed and desired to secure by Letters Patent:

1. A tool attachment, comprising, a positioning block having a hole therein, a tool having a shank insertible within said hole and provided with an 55 abutment, a supporting member, and clamping means coacting directly with said abutment for detachably fastening both said tool and said block directly to said member.

2. A tool attachment, comprising, a positioning 60 block having a bore, a tool having a cylindrical shank insertible within said bore and provided with an integral side abutment, a supporting member, and a clamping screw having a head coacting directly with said abutment and a threaded 65 portion coacting with said member to detachably fasten both said tool and said block to said member.

3. A tool attachment, comprising, a positioning 70 block having a hole therein, a tool having a shank insertible within said hole and provided with an abutment, and a clamping screw coacting with said block adjacent to said hole, said screw having an integral head cooperable directly with said abutment and said head being provided with a 75 cut-out positionable adjacent to the tool shank

upon rotation of said screw so as to permit removal of said tool without removing said screw.

4. A tool attachment, comprising, a positioning block having a hole therein, a reaction plate coacting with said positioning block, a tool having a shank insertible within said hole in contact with said plate and provided with an abutment, a supporting member, and clamping means coacting directly with said abutment for detachably fastening said tool, block, and plate directly to 10 said member.

5. A tool attachment, comprising, a positioning block having a bore, a reaction plate coacting with said block and projecting beyond said bore, a tool having a cylindrical shank insertible 15 within said bore against said plate and provided with an integral side abutment, a supporting member coacting with said plate, and a clamping screw coacting directly with said abutment and having a threaded portion coacting with said 20 member for detachably fastening said tool, block, and plate to said member.

6. A tool attachment, comprising, a positioning block having a hole therein, a supporting member for said block, a dowel pin for preventing 25 displacement of said block relative to said supporting member, a tool having a shank insertible within said hole and provided with an abutment, and clamping means coacting directly with said abutment for detachably fastening said tool and 30 said block directly to said member and for preventing rotation of said tool.

7. A tool attachment, comprising, a positioning block having a bore, a supporting member for said block, a dowel coacting with said block and 35 with said member to prevent displacement of said block, a tool having a cylindrical shank insertible within said bore and provided with a recess forming an abutment disposed within the wall of said bore, and a clamping screw having a head 40 coacting with said abutment and a threaded portion coacting with said member for detachably fastening said tool and said block to said member while preventing rotation of said tool about its own axis.

45 8. A tool attachment, comprising, a positioning block having a bore, a tool having a cylindrical shank insertible within said bore and provided with a cut-out forming an integral abutment, and a clamping screw having a cylindrical 50 head cooperable with said abutment to lock said tool within said bore and to prevent rotation of said tool about its own axis, said screw head having a recess registerable with the wall of said bore to permit endwise removal of said tool from said 55 block.

9. A tool attachment comprising, a positioning block having a bore, a reaction plate coacting with said block and spanning an end of said bore, a supporting member for said block and plate, a 60 dowel for positioning said block and said plate relative to said member, a tool having a cylindrical shank insertible within said bore against said plate and provided with an abutment, and a single clamping screw having a head coacting with 65 said abutment and a threaded portion coacting with said member for detachably fastening said tool, block, and plate to said member, and for positively preventing rotation of said tool about its own axis.

70 10. A tool attachment, comprising, a positioning block having a bore extending therethru, a reaction plate coacting with said block and closing one end of said bore, a supporting member for said block and plate coacting only with said 75

plate, a tool having a shank snugly fitting said bore and provided with an abutment disposed within the confines of said bore, and a single clamping screw extending parallel to the axis of said tool and having a cylindrical head coacting with said abutment and a threaded portion coacting with said member to detachably fasten

said tool, block, and plate to said member, said screw head normally preventing rotation of said tool about its own axis and being provided with a cut-out registrable with said bore for effecting endwise removal of said tool from within said bore.
